UNITED STATES PATENT OFFICE.

ALBERT H. TUTTLE, OF CAMBRIDGE, MASSACHUSETTS.

SUCTION APPARATUS FOR SURGICAL USE.

1,316,340.

Specification of Letters Patent. Patented Sept. 16, 1919.

Application filed November 6, 1918. Serial No. 261,416.

To all whom it may concern:

Be it known that I, ALBERT H. TUTTLE, a citizen of the United States, residing at Cambridge, in the county of Middlesex and 5 State of Massachusetts, have invented new and useful Improvements in Suction Apparatus for Surgical Use, of which the following is a specification.

This invention has for its object to provide a siphon adapted for surgical use in drawing liquid from the body of a patient, and of such construction that a portion of the siphon may at the outset receive a flow-inducing charge of liquid, which, in flowing 10 from the outlet end of the siphon, creates a vacuum between the outlet and intake ends, and thereby causes a siphonic flow which may be practically continuous, the liquid flowing from the siphon being constantly replenished by liquid drawn from 15 the patient's body.

The invention is embodied in the improvements which I will now proceed to describe and claim.

25 Of the accompanying drawings, forming part of this specification:

Figure 1 is a sectional view, showing an apparatus embodying the invention in position for operation.

30 Fig. 2 is a view similar to Fig. 1, the apparatus being inverted and the reducer hereinafter described being removed, to provide an opening for charging and clean-out purposes.

35 Fig. 3 is an enlargement of a portion of Fig. 1.

Figs. 4 and 5 are plan views of the outlet-forming disks shown by Fig. 3.

Fig. 6 is a side elevation of another form 40 of apparatus embodying the invention.

Fig. 7 is a section on line 7—7 of Fig. 6.

Fig. 8 is an end view of the reducer shown by Fig. 7, removed from the reservoir.

45 Fig. 9 is a sectional view illustrating a modification.

The same reference characters indicate the same parts in all of the figures.

My improved siphon comprises a portable reservoir constituting one end portion 50 of the siphon and adapted to receive a flow-inducing charge of liquid, and to be conveniently cleaned out when this is necessary, and an elongated flexible tube connected with the reservoir and constituting the opposite end portion of the siphon, said tube

preferably having at its intake end a suitable terminal, such as a catheter, adapted to be inserted in a cavity of a human body.

Referring first to Figs. 1 and 2, 12 represents the reservoir, which may be an elongated cylinder, and is provided at one end portion with a relatively large opening 13, adapted for use in charging and cleaning out the reservoir, and here shown as formed by an externally screw-threaded neck 13^a 60 through which liquid escapes from the reservoir. The reservoir is provided at its opposite end portion with a relatively small opening 14, here shown as formed by a nipple, through which liquid enters the 70 reservoir. The reservoir is elsewhere closed and imperforate.

A closure, having relatively adjustable members forming a variable reservoir outlet, is separably connected with the clean-out opening 13, said closure in this case comprising a flanged cap 15, which is screw-threaded to engage the thread of the neck 13^a and is provided with a large opening 16, and a pair of thin metal disks or outlet-forming members 17 and 18. The larger member 17 is clamped between the neck 13^a and the flange of the cap 15, and is provided with a plurality of orifices 19 of different sizes. The smaller member 18 is pivoted 80 by a bolt 20 to the member 17, and is provided with an orifice 21 of the same size as the largest orifice 19, the arrangement being such that the orifice 21 may be caused to register with either of the orifices 19 by 90 turning the member 18, which is provided with a handle 22. The member 18 is pressed closely against the member 17 by a spring 23 between the member 18 and a nut 24 on the bolt 20. 25 represents the flexible tube, 95 which is preferably made wholly or in part of rubber, and is connected at one end with the nipple 14. The tube 25 may be provided at its intake end with a suitable terminal, adapted for surgical use, such as a 100 catheter 26.

The above-described apparatus is operated as follows:

The closure being removed, and the reservoir inverted, as shown by Fig. 2, a charge 105 of water or other liquid is introduced through the opening 13 into the reservoir. The siphon is temporarily closed by any suitable means, such as a clamp 27, applied to the flexible tube 25 to flatten the latter at 110

a given point, and thus prevent the escape of liquid from the reservoir when the latter is inverted. The clamp here shown is of well-known construction, and any other suitable closing device may be substituted therefor. The closure is next applied to the opening 13, and the reservoir is turned to the position shown by Fig. 1, the inlet 14 being located above the outlet. Suitable means, such as a bail 28 fixed to the reservoir may be provided for supporting the reservoir in the last-mentioned position, said bail being adapted to be engaged by a hook, or other suspensory, engaged with a portion of a bedstead. Two bails 28 are here shown, these being at opposite sides of the reservoir. When the reservoir is suitably located and supported, the terminal 26 is applied to the patient to receive liquid to be removed. The clamp 27, when closed, causes the retention of the charge of liquid in the reservoir by atmospheric pressure. When the clamp is opened, the liquid in the reservoir commences to flow through the adjustable outlet provided by the orifice 21 and one of the orifices 19, so that a vacuum is at once formed in the upper part of the reservoir and in the tube 25. A flow of liquid from the patient's body is therefore induced, the liquid entering the reservoir and replacing that discharged through the outlet thereof, so that the action of the siphon is continuous so long as liquid flows through the tube 25. The action may be interrupted at any time by closing the clamp 27. The reservoir may be cleaned out whenever necessary through the opening 13, the closure being removed. A relatively large opening 13 is essential, not only for reservoir charging, but also for reservoir cleaning.

Figs. 6, 7 and 8 illustrate a different embodiment of the invention, in which the reservoir 12 is provided with legs at its lower end, a tube-engaging nipple 14 at its upper end, and a charging and clean-out opening formed by an internally screw-threaded neck 30 projecting laterally from the wall of the reservoir at or near its lower end. A closure, having relatively adjustable members forming a variable outlet, is separably connected with the neck 30. Said closure, as shown by Figs. 7 and 8, includes an externally threaded plug portion 31, engaged with the internal thread of the neck, having a flat head 31^a, constituting one of said outlet-forming members, with a plurality of orifices 32 of different sizes, and with an externally threaded flange 33, a sleeve or collar 34 internally threaded to engage the flange 33, and a rotary valve body comprising a head 35, and a tubular shank 36, provided with an annular handle or grip portion 37, secured to the shank by a key 38 and a nut 39 engaging an external thread on the shank. The bore 40 of the tubular shank is

of substantially the same diameter as the largest orifice 32, and has an offset portion 40^a adapted to register with either of said orifices. The head 35, which constitutes the other outlet-forming member, is pressed against the plug head 31^a by a spring 42 between said head and an internal flange 43 on the sleeve 34. The handle 37 is externally roughened, as by knurling or milling, so that it may be effectively grasped by a hand, and turned to bring the offset bore portion 40^a into registration with either of the orifices 32. The valve may be yieldingly maintained in a plurality of operative positions by a spring bolt 45 in the sleeve 34, having a rounded end, and a series of concave depressions 46 in the handle 37. The shank 36 may be extended to form a nipple 36^a, adapted to engage a flexible waste-conducting tube. The closure may be readily removed by unscrewing the plug portion thereof from the neck 30, thus enabling the reservoir to be cleaned out and charged.

By providing means as described in each embodiment of the invention for varying the size of the reservoir outlet, I am able to time the duration of the flow of liquid through the siphon and enable the apparatus to withdraw liquid from the patient's body either slowly and for a relatively long uninterrupted period, or rapidly and for a shorter uninterrupted period. For example, when the smallest orifice 19 or 32 is in operative position, liquid such as serum originating in the patient's body, is permitted to escape very slowly, as drop by drop, and for an uninterrupted period of several hours, so that one quart or less may be drawn automatically in say twenty-four hours. When the largest orifice 19 or 32 is in operative position, liquid is permitted to flow in a stream of approximately half an inch in diameter, so that several quarts per minute may be drawn, thus providing for the rapid uninterrupted withdrawal from the patient's body of water introduced into a cavity therein for flushing or cleansing purposes.

As shown by Fig. 9, the reservoir may be provided with a charging and clean-out opening 48, which is independent of the siphon outlet and is provided with a removable closure 49, having a nipple 50 for connection with the tube 25, so that the tube may discharge through the opening 48, the closure 49 being a reducer.

The outlet may be a faucet 51 of ordinary construction, the valve or plug of the faucet constituting an equivalent of the clamp 27, as a siphon-closing means.

In each of the illustrated embodiments of the invention, the reservoir is provided with only two openings, and with means for preventing the use of the larger opening for charging and clean-out purposes when the apparatus is in use.

In each of said embodiments the reservoir is provided with positioning means, such as a bail 28, (Figs. 1 and 2), or the legs shown by Figs. 6 and 9, adapted to be 5 separably engaged with a support, such as a bed frame or a floor, and to coöperate with the support in maintaining the reservoir at a predetermined height, the portability of the reservoir and the separability of its 10 positioning means from the support enabling all of the required adjustments and manipulations of the siphon to be effected.

I claim:

1. A suction device for surgical use, comprising a flexible tube having an intake end formed to be inserted in a body cavity, and a reservoir having at one end a contracted inlet connected with the delivering end of the tube, and at the opposite end a contracted outlet, said tube and reservoir constituting an elongated partially flexible conduit, adapted to be formed into a siphon of which the intake end portion of the tube constitutes the shorter leg, and the reservoir 25 a longer-leg-enlargement rendering the siphon automatic and adapted to be charged with liquid to form a liquid piston and to retain sufficient additional liquid drawn from the body to maintain said piston, the 30 device being portable and the reservoir supportable in a position lower than the said intake end portion, means being provided for closing the siphon.

2. A suction device for surgical use, comprising a flexible tube having an intake end formed to be inserted in a body cavity, and a reservoir having at one end a contracted inlet connected with the delivering end of the tube, and at the opposite end a contracted 40 outlet, said tube and reservoir constituting an elongated partially flexible conduit, adapted to be formed into a siphon of which the intake end portion of the tube constitutes the shorter leg, and the reservoir a longer-leg-enlargement rendering the siphon 45 automatic and adapted to be charged with liquid to form a liquid piston and to retain sufficient additional liquid drawn from the body to maintain said piston, the device being 50 portable and the reservoir being provided with positioning means adapted to be separably mounted on a support to maintain the reservoir in a position lower than the said intake end portion, means being 55 provided for closing the siphon.

3. A siphon for surgical use provided with means whereby it may be opened and closed, said siphon comprising a portable and invertible reservoir having at one end 60 portion a contracted inlet and at the opposite end portion a contracted outlet, and provided with positioning means adapted to be separably engaged with a support and to coöperate therewith in maintaining the reservoir at a predetermined height with the 65 reservoir at a predetermined height with the

inlet located above the outlet, and an elongated flexible tube connected at one end with said inlet and adapted at its opposite end to receive liquid from a patient's body, said reservoir having a charging and clean-out opening and a removable closure for said opening, preventing the use of the opening for charging and clean-out purposes when the siphon is in use. 70

4. A siphon for surgical use provided with means whereby it may be opened and closed, said siphon comprising a portable reservoir having at one end portion a contracted inlet and at the opposite end portion a contracted outlet, and provided with 80 positioning means adapted to be separably engaged with a support and to coöperate therewith in maintaining the reservoir at a predetermined height with the inlet located above the outlet, and an elongated flexible 85 tube connected at one end with said inlet and adapted at its opposite end to receive liquid from a patient's body, said reservoir having a charging and clean-out opening at the end opposite the contracted inlet and a removable closure for said opening having outlet-forming members which provide a 90 variable outlet.

5. A siphon for surgical use provided with means whereby it may be opened and closed, said siphon comprising a portable reservoir having at one end portion a contracted inlet and at the opposite end portion a contracted outlet, and provided with means whereby it may be mounted on a support with the inlet located above the outlet, and an elongated flexible tube connected at one end with said inlet and adapted at its opposite end to receive liquid from a patient's body, said reservoir having a 95 charging and clean-out opening and a removable closure therefor having outlet-forming members one of which is fixed and the other movable, one of said members having a single relatively large orifice and the other a series of orifices of different sizes. 100

6. A siphon for surgical use provided with means whereby it may be opened and closed, said siphon comprising a portable reservoir having at one end portion a contracted inlet and at its opposite end a charging and clean-out opening having means forming a contracted outlet, and a flexible tube connected at one end with said inlet and adapted at its opposite end to receive liquid from a patient's body, said reservoir being provided with positioning means adapted to be separably engaged with a support and to coöperate therewith in maintaining the reservoir at a predetermined height, with the inlet located above the outlet. 115

7. A siphon for surgical use provided with means whereby it may be opened and closed, said siphon comprising a portable 120

reservoir having at one end portion a contracted inlet and at its opposite end portion a charging and clean-out opening, a removable closure for said opening having
5 outlet-forming members which provide a variable contracted outlet, and a flexible tube connected at one end with said inlet and adapted at its opposite end to receive liquid from a patient's body, said reservoir
10 being provided with means whereby it may be mounted on a support with the inlet located above the outlet.

8. A siphon for surgical use provided with means whereby it may be opened and
15 closed, said siphon comprising a portable reservoir having at one end portion a contracted inlet and at its opposite end portion

an outwardly projecting tubular neck forming a filling and clean-out opening, a removable closure for said opening having a 20 fixed member, a movable member, said members being adapted to coöperate in forming a variable contracted outlet, and external means for turning said movable member to vary said outlet and a flexible tube connected 25 at one end with said inlet and adapted at its opposite end to receive liquid from a patient's body, said reservoir being provided with means whereby it may be mounted on a support with the inlet located above the outlet.

In testimony whereof I have affixed my signature.

ALBERT H. TUTTLE.
